UNITED STATES PATENT OFFICE.

RUDOLPH F. STEHLIK, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

TELEPHONE SYSTEM.

Application filed May 11, 1925, Serial No. 29,373. Renewed May 18, 1928.

The present invention relates in general to telephone systems, but is concerned more particularly with telephone systems of the type in which so-called "finder switches," that is, backward hunting switches, are employed to connect a calling line with an idle trunk line; and a special object of the invention is the production of a new and improved sending arrangement to be used in connection with finder systems of the directive-finder type whereby there is no loss of time between the two directing digits transmitted to a finder and between the second of the digits and the switching-through operation.

The above result is secured, preferably by a separate sending switch for each digit and by arranging the circuits so that the sequence switch which controls the transmission of the digits to the finders, and the switching-through operation so that the magnet of the sequence switch is energized in parallel with the magnet of the sending switch during the transmission of the last impulse of each series to the finder being operated.

According to another feature, a vertical marking wiper is provided on the first sender to mark the level to which the finder is raised and to render the second sender controllable from lines in that level only so as to prevent possible calling lines in the other levels from interfering with the operation of the second sender to stop the finder on the wrong set of contacts.

According to a further feature of the case, a unique impulse control arrangement is employed whereby the length of the impulses transmitted to the various finder magnets is automatically varied to suit the particular magnet being operated. More specifically, the termination of each impulse is under the control of the magnet to which the impulse is sent.

According to another feature of the case, arrangements are provided such that in case the magnet being operated is unable to terminate the impulses, due, for example, to dirty contacts, a timing arrangement associated with the sending apparatus, but not normally effective due to the speed at which the impulses are terminated, becomes effective to terminate the impulses and to operate the magnet in the usual manner, although at a slower rate than if it were able to exercise the intended control over the sending operation.

A further feature of the case relates to the provision whereby the secondary switch which is used to connect a finder with a first selector is rendered preselecting as soon as the finder is allotted. It is a special feature of the case, however, that the preselected trunk is not seized and made busy to the exclusion of its use by secondary switches in other groups until the allotted finder is actually taken for use upon the initiation of a call in the associated group of lines.

The remaining features relate, for the most part, to the circuit details involved in carrying out the foregoing, and these will be understood the best from the detailed description which is to follow.

Referring now to the accompanying drawings comprising Figs. 1-4, they can be understood best when Fig. 2 is placed to the right of Fig. 1, with Fig. 3 under Fig. 1, and with Fig. 4 below Fig. 3. When laid out in this manner these drawings represent, by means of the usual circuit diagrams, a sufficient amount of apparatus in a telephone system employing the new and improved finder system to enable the invention to be understood.

Referring now to Fig. 1, this drawing shows the automatic substations A and A'. The lines associated with the substations terminate in the banks of the finder F as well as in the connector banks shown at the left. These lines are provided with the usual line and cut-off relays 2-5.

The finder F, also shown in Fig. 1, is controlled, when allotted by the finder allotter FA, from the sending mechanism shown in Figs. 3 and 4 to connect with any one of the 100 lines to which it has access.

The secondary hunting switch SS, Fig. 2 is used to connect the finder F with an idle first selector, such as FS, and it is connected to the finder F, Fig. 1, through the medium of the intermediate distributing frame IDF which is employed in order to enable the desired cross-connection between the various primary groups in which the finders are located and the various secondary groups in which the secondary switches are located to be made in any desired manner.

Fig. 3 shows the relays 221-229 which are used to control the sending operation, which includes the control of the switching mechanisms shown in Fig. 4, and also are used to

control the operations of the finder allotter FA Fig. 1. This drawing shows also the switch S associated with the relay 201 which is used to close a circuit for the relay 201 when it is desired to energize this relay to disconnect the controlling relays 221—229, from the finder allotter FA Fig. 1, and to connect it instead to the spare allotter (not shown). This operation is performed, it will be understood, in case an attendant wishes to test or adjust the finder allotter FA. In this way the service is not interrupted at such times.

Fig. 4 shows the vertical sender VS which is used to control the finders in their vertical operation; it shows the rotary sender RS which is used to control the finders in their rotary operation; and it shows also the sequence switch SE which is employed for the purpose of controlling the sequence of operations of the two senders VS and RS, and to effect the switching-through operation at the end of the operation of the rotary sender RS.

Regarding the mechanical construction of the equipment shown, it may be pointed out that the finder F and the first selector FS are both of the well known vertical and rotary type of switch, having bank contacts arranged in horizontal rows or levers. The finder F, however, is modified in that its wipers, instead of standing one step below the first level of the bank contacts as in the ordinary case, stand opposite the first level of the bank contacts so that in case the wipers are to be brought into engagement with a set of contacts in the first level they need not be first raised but are rotated right away. It will be noted that the lever 57 which controls the off normal springs 50, etc., is slanted at the end so that in case the arm 58, of which an end view only is shown, moves to the left when the wipers are rotated into engagement with contacts in the first level the lever 57 is permitted to rise as is also the case when the lever 58 is first moved vertically. An arrangement of this nature is shown more in detail in my co-pending application filed May 19, 1924, Serial No. 714,188.

Mechanically, the finder allotter FA is, as shown, a simple rotary switch of the well known type in which the wipers are advanced step by step by an associated stepping magnet and in which the wipers are advanced upon restoring stroke of the armature, rather than upon the operating stroke. The secondary switch SS, Fig. 2, the sending switches VS and RS, Fig. 4, and the sequence switch SE, Fig. 4, are all similar, mechanically, to the finder allotter FA.

Referring again to Fig. 3, the functions of each of the relays 221—229 will be pointed out separately in order to facilitate a ready understanding of the detailed operation to be later described.

Relay 221 is the first-level control relay.

It is energized responsive to a call over a line terminating in the first level of the finders and it operates to prevent the operation of the vertical magnet of the allotted finder by opening the vertical magnet circuit at armature 241, and to prevent the operation of the vertical sender VS, Fig. 4, and to operate the sequence switch SE right away by shifting the control circuit at armature 243.

Relay 222 is the secondary-line-switch 75 switching relay, so called because it occupies the same position in the circuit as the switching relay of an ordinary rotary line switch. This relay pulls up when the secondary line switch finds an idle trunk in case relay 226 is 80 energized.

Relays 223 and 224 are the emergency stepping relay and the regular stepping relay, respectively. Relay 224 is controlled over conductor 79 to open the impulse circuit as 85 soon as the magnet to which the impulse circuit is connected operates.

Relay 223 is slow to pull up. Its circuit is closed each time the impulse circuit is closed, but does not ordinarily have sufficient time to 90 operate before the regular stepping relay 224 is pulled up, but, in case the contacts of the magnet fail to close (due to bad adjustment or to dirty contacts, etc.), the emergency stepping relay 223 pulls up after an interval 95 which is slightly longer than the time required for the average magnet to operate and terminates the impulse being delivered.

Relays 225 and 226 are the auxiliary start relay and start relay, respectively. Relay 100 225 is provided primarily as a circuit closing relay on account of the great number of contacts that need to be closed when the start wire is grounded.

Relay 227 performs several functions and 105 is called the guard relay because the upper winding of this relay is energized in a branch circuit with the magnet 77 of the finder allotter FA, Fig. 1, to maintain the start relay 226 disconnected during the hunting operation of 110 the finder allotter, and because the lower winding of the guard relay 227 is energized from armature 264 of the series guard-control relay 228, which remains energized during the restoration to normal of the vertical sender 115 VS and the rotary sender RS.

Relay 228 is the busy relay and it energizes through resistance 230 when ground is removed from conductor 88 responsive to the condition of all finders such as F being busy 120 or otherwise unavailable.

The detailed description of the operation of the apparatus shown will now be given. For this purpose it will be assumed first that the subscriber at substation A, whose line 125 is No. 25 in the finder book, desires to make a call and that he accordingly removes his receiver.

When the receiver is removed at substation A, a circuit is closed over the conductors of 120

the associated line for line relay 3. Line relay 3 thereupon energizes and, in addition to grounding the start conductor 12 at armature 8, closes certain control circuits at armatures 6 and 7. The control circuit closed at armature 7 is the second-level vertical-control circuit and is used to control the finder to bring its wipers opposite the second level of bank contacts. The circuit closed at armature 6 is the No. 25 rotary control circuit and is used to guide the wipers of the finder into engagement with the fifth set of bank contacts in the second level after they have been raised opposite that level.

When the common start conductor 12 is grounded at armature 8 of line relay 3, as above pointed out, a circuit is closed over conductor 12 and through armature 259 and its resting contact for start relay 226 which is connected to battery through the switching room supervisory relay 231. Start relay 226 accordingly energizes and closes at armature 257 a circuit for the auxiliary start relay 225. At armature 255, relay 226 disconnects the combined cut-through and test conductor from the test conductor from the test circuit of the finder allotter FA, Fig. 1, and connects it instead to an open branch of the cut-through circuit, preparatory to the subsequent closure of the cut-through circuit; at armature 256 it places a shunt around the resting contact and armature 260 of guard relay 227 for a purpose to be pointed out hereinafter; and at armature 258 it disconnects ground from the busy relay 229 to prevent its premature operation under certain conditions to be hereinafter explained; and at armature 258 and its front contact it connects ground to the secondary switching relay 222, whereupon relay 222 energizes over a circuit which includes armature 208 and its resting contact, conductor 85, wiper 76 of the finder allotter FA, the first bank contact, jumper 55, self-interrupting contacts 105, and the secondary stepping magnet 104. Magnet 104, however, is not operatively energized at this time on account of the relatively high resistance of the switching relay 222, Fig. 3. Relay 222, upon energizing, closes a second point in the cut-through circuit at armature 244, and at armature 245 it opens the connection which previously existed between the stepping magnet 104 of the secondary switch SS and the test wiper 102 and places ground on test wiper 102 through armature 205 and its resting contact, conductor 82, wiper 73 of the finder allotter FA, the first associated bank contact, and the jumper 54. The result of this latter operation is to guard the preselected first selector FS, Fig. 2, from seizure.

Returning now to the auxiliary start relay 225, Fig. 3, whose circuit is closed at armature 257 of start relay 226, the closure of the circuit of this relay resulted in its energization, whereupon it closes at armature 250 a circuit through armature 206 and its resting contact, conductor 83, and wiper 74 of the finder allotter FA for the release guard relay 37 of the finder F. Relay 37 now energizes and prepares at armature 47 a circuit for the cut-through relay 36, and at armature 48 opens a point in the circuit of release magnet 39, in addition to preparing a certain guarding circuit to be hereinafter pointed out. As a further result of its energization, the auxiliary start relay 225 places a local ground on the start conductor 12 at armature 251 so as to maintain the start relay 226 energized independent of the calling line until the common controlling apparatus has gone through its complete sequence of operation. At armature 252 relay 225 places a shunt around the self-interrupting contacts 78 of the finder allotter stepping magnet 77 for a reason which will become apparent upon a further perusal of the description. As a still further result of its operation, the auxiliary start relay 225 at armature 253 disconnects the first-level-control relay 221 from the first-level-control-terminal 269 so as to prevent a possible calling line in the first level from energizing relay 221 to interfere with the call after it has once gotten under way; and at armature 254 relay 225 places ground on conductor 270, thereby closing a circuit through the resting contact and armature 263, armature 248 and its resting contact, conductor 280, wiper 313 of the sequence switch SE in its first position, the vertical magnet operating conductor 274, armature 241 and its resting contact, armature 203 and its resting contact, conductor 80, wiper 71 of the finder allotter FA, and vertical magnet 34 to battery. Vertical magnet 34 is thereupon energized and it raises the wipers 31-33 from their normal position opposite the first level of bank contacts to a position opposite the second level of bank contacts.

In the common controlling apparatus, Fig. 3, the placing of ground upon conductor 270 by armature 254 of the auxiliary start relay 225, also extends a ground potential through armature 249 and its resting contact to the sender impulse distributing wiper 312 of the sequence switch SE. This ground potential is extended through wiper 312 in its first position, conductor 277, armature 243 and its resting contact, and conductor 271 to the stepping magnet 301 of the vertical sender VS. Accordingly, stepping magnet 301 energizes preparatory to advancing the wipers 307-309 on its restoring stroke when its circuit is subsequently opened. It will be noted further that the ground potential is extended to the terminal 321 which is a common connecting point, it may be pointed out, for the vertical control conductors (such as the vertical control conductor 16 of the second level) 130

of all the levels with the exception of the first level. Now, since the level in which the calling line terminates is the second level, and since the wipers normally stand opposite the first level, only one vertical step is required to reach the calling level. Accordingly, a circuit is now closed from the grounded terminal 321 over conductor 16, armature 7 and its working contact, conductor 17, terminal 292 which corresponds to the second level of bank contacts of the finders, first contact in the bank of wiper 308 and the said wiper, and the first contact in the bank of wiper 314 and said wiper for stepping magnet 303 of the sequence switch SE. Accordingly, magnet 303 energizes in multiple with stepping magnet 301 of the vertical sender VS and in multiple with vertical magnet 34 of the finder F, preparatory to advancing wipers 312—314 to their second position to terminate the vertical movement and to initiate the rotary movement as soon as the first impulse is terminated.

As a further result of the above mentioned energization of vertical magnet 34 of the finder F, it closes its sending contacts 40, thereby placing ground upon the stepping-relay-control conductor 79 which is common to the group of finders served by the finder allotter FA. That being the case, a circuit is closed over conductor 79 for stepping relay 224, Fig. 3. Responsive to the closure of this circuit stepping relay 224 pulls up and opens at armatures 248 and 249 the above traced circuit for the stepping magnets 301 and 303 of vertical sender VS and the sequence switch SE, respectively. Accordingly, magnets 301 and 303 fall back and advance their respective associated wipers one step, and vertical magnet 34 of the finder F falls back and removes ground from conductor 79, whereupon stepping relay 224, Fig. 3, again falls back to transmit the next impulse.

Since the sequence switch SE has now advanced its wipers 312—314 from the first position to the second position, no more impulses can be sent over conductor 274 to vertical magnet 34 of the finder F, and the impulses subsequently generated are accordingly transmitted over conductor 275 and over a path to be subsequently traced to rotary magnet 35 of the finder F. Also, due to the fact that wiper 314 has advanced from the first contact, which is associated with the vertical control wiper 308 of the vertical sender VS, to its second contact, which is associated with the rotary control wiper 311 of the rotary sender RS, the further advance 50 of the sequence switch SE to terminate the second digit to be transmitted to the allotted finder is under the control of the rotary-control wiper 311. Furthermore, it will be noted that the sender impulse distributing wiper 312, being now on its second contact, has dis-

connected the sender impulse conductor 279 from conductor 277 leading to stepping magnet 301 of the vertical sender by way of armature 243 and its resting contact and conductor 271, and has connected it instead to stepping magnet 302 of the rotary sender RS.

Upon the falling back of stepping relay 224, ground from the grounded conductor 270 through the resting contact and armature 263 is again extended at armature 248 by way of conductor 280 to the finder-impulse distributing wiper 313 of the sequence switch SE. Accordingly, a ground potential is extended further through the second contact in the bank of wiper 313 through conductor 275, armature 264 and its resting contact, conductor 81, and wiper 72 and its first contact to rotary magnet 35 of the finder F. By the operation of rotary magnet 35, the wipers 31—33 are rotated into engagement with the first set of bank contacts in the second level.

In the common sending equipment, the falling back of stepping relay 224, Fig. 3, results also in the closure at armature 249 of a circuit from the grounded conductor 270, over conductor 279, and through wiper 312 and its second bank contact for stepping magnet 302 of the rotary sender RS. Accordingly, stepping magnet 302 energizes preparatory to advancing the wipers 310 and 311 one step when the above traced circuit is opened.

It may be pointed out further at this time that if the calling line were No. 21 instead of No. 25 a circuit would also be closed at this time through the first contact of the rotary control wiper 311 and through the second contact in the bank of wiper 314 and the said wiper for stepping magnet 303 of the sequence switch SE to terminate the rotary operation after the first impulse, but since this is not the case, the rotary control circuit closed over conductors 18 and 19 at armature 6 of relay 3 returns over conductor 19 to the common terminal 293 which is connected to the fifth contact in the bank of the rotary control wiper 311 instead of the first. It may be pointed out further, that due to the action of the vertical marking wiper 309 of the vertical sender VS, the impulse lead which wiper 309 terminates is connected to terminal 295 common to all lines in the second level to the exclusion of terminals such as 294 common to the other levels, respectively. Accordingly, it may be seen that the rotary control connections of lines in levels other than the second level can have no effect at this time.

In the finder F, as a further result of the energization of rotary magnet 35, it places ground at the sending contact 41 upon the common stepping-relay control conductor 79, thereby closing a circuit for stepping relay 224. Accordingly, relay 224 pulls up and at armatures 248 and 249 opens the cir-

cuits of rotary magnet 35 of the finder F and stepping magnet 302 of the rotary sender RS, respectively. Stepping magnet 302 now falls back and advances the wipers 310 and 311 one step, whereupon wiper 311 disconnects ground from the first rotary control conductor and connects it instead to the second rotary control conductor. When rotary magnet 35 falls back and at contacts 41 re-
 10 moves ground from conductor 79, stepping relay 224, Fig. 3, again falls back and at armatures 248 and 249 closes the circuits of magnet 35 of the finder F and magnet 302 of the rotary sender RS, respectively.
 15 This alternate operation of the magnets 35 and 302 and stepping relay 224 continues as described until four impulses of current have been delivered to rotary magnet 35 of the finder F and to stepping magnet 302 of
 20 the rotary sender RS, and when magnet 302 falls back at the end of the fourth impulse and advances wiper 311 into engagement the fifth contact (in which the fifth rotary control conductor terminates), a circuit is
 25 prepared for operating stepping magnet 303 of the sequence switch SE in multiple with magnet 302 upon the next impulse. That being the case, when the circuit is next completed and current is next transmitted to
 30 wiper 312 of the sequence switch SE in its second position to operate magnet 302 of the rotary sender RS, coincident to the transmission of the fifth impulse to the rotary magnet 35 of the finder F, a circuit in multiple with magnet 302 is closed through the vertical marking wiper 309, second associated bank contact, the terminal 295 common to the lines in the second level of the finders, rotary-control conductor 18, working contact of armature 6 and said armature, conductor 19, terminal 293, common to all fifth rotary step lines, fifth contact in the bank of wiper 311 and said wiper, second contact in the bank of wiper 314 and the said wiper
 35 and magnet 303 to battery. Accordingly, 303 energizes preparatory to advancing the wipers 312—314 when it subsequently falls back.
 In the finder F, the wipers 31—33 have at this time been advanced to the fifth bank contact in the second level by the operation of rotary magnet 35.
 40 In the common sending equipment, Fig. 3, when stepping relay 224 pulls up responsive to the fifth grounding of conductor 79 by rotary magnet 35 of the finder F, it again opens the impulse circuit at armatures 248 and 249 whereupon magnet 35 of the finder F and magnets 302 and 303 of the switches RS and SE, Fig. 4, respectively fall back.
 45 The deenergization of magnet 302 results merely in an incidental advance of wipers 310 and 311 another step. The deenergization of stepping magnet 303 of the sequence switch SE results in the advance of wipers 312—314 another step from the rotary send-

ing position to the switching-through position. The sequence switch control wiper 314, upon advancing to the third contact, encounters the grounded conductor 276, whereupon magnet 303 energizes preparatory to advancing the wipers out of position 3 into position 4. The finder-impulse distributing wiper 313 engages a dead contact in the third position. The sender-impulse distributing wiper 312 in its third position connects with the cut through conductor 278 over which the cut through operation is to be controlled subsequently.

In the finder F, rotary magnet 35 falls back responsive to the termination of the fifth impulse and removes ground from conductor 79, whereupon stepping relay 224, Fig. 3 falls back and at armature 249 again extends ground to the sender impulse distributing wiper 312. This results in a ground potential being extended over connector 278 to the upper winding of the combined guard and cut-through control relay 227. A branch of this circuit extends through armature 209 conductor 86, and contacts 78 to magnet 77 of the finder allotter FA. Magnet 77 energizes preparatory to advancing the wiper 71—76 when it subsequently falls back. Although it opens its own circuit, as traced, at contacts 78, magnet 77 does not fall back responsive thereto owing to the fact that contacts 78 are shunted by armature 252 and its working contact of relay 255 through a connection which included armature 210 and its resting contact and conductor 87.

As a result of the above mentioned closure of the circuit of the upper winding of the combined guard and cut-through control relay 227 Fig. 3, this relay pulls up and at armature 259 disconnects the start conductor from the slow acting start relay 226, at the same time completing the cut through circuit. Start relay 226 does not fall back at this time it may be pointed out on account of the fact that it is slow acting. The cut through circuit extends from ground on the grounded start wire 12 through armature 259 and its working contact, working contact and armature 244, working contact and armature 255, armature 207 and its resting contact, conductor 84, wiper 75 of the finder allotter FA, the first associated bank contact, off normal spring 50 and its upper contact, armature 47 and its working contact, relay 36, and resistance 38 to battery. Relay 36 energizes over the above traced circuit unless the line of substation A has become busy during the time elapsing between the removal of the receiver and the arrival of the finder F due to a call being extended to the line through the connector bank terminals shown at the left. Assuming the line to be still in the idle calling condition, relay 36 pulls up and extends the line conductors of the calling line by the way of working contacts of and armatures 42

and 46 over the heavy talking conductors shown to the first selector FS Fig. 2. Relay 36 at armature 43 also disconnects the test wiper 32 from the junction of resistance 38 and relay 36 and connects it to ground instead, thereby closing a circuit over the private normal conductor of the line of substation A for the cut off relay 2, which thereupon energizes and disconnects ground and line relay 3 from the line of substation A. Line relay 3 now falls back and separates conductors 18 and 19 and conductors 16 and 17 at armature 6 and 7, and at armature 8 removes ground from the start conductor 12, leaving this conductor grounded in the common equipment at armature 251 of the auxiliary start relay 225, Fig. 3. As a further result of energization of relay 36 of finder F, this relay locks itself to the grounded release trunk conductor 72 at armature 44, and at armature 45 opens a further point in the circuit of release magnet 39.

In the first selector FS, Fig. 2, line relay 121 energizes responsive to the final extension of the calling line at relay 36 of finder F, as above pointed out, and closes at armature 131 a circuit for release relay 122. Release relay 122 now energizes and at armature 133 places ground on release trunk conductor 109 so as to maintain the connection between the first selector and the calling line through the finder F and the secondary switch SS independent of the common controlling equipment which is to be shortly associated with another finder-secondary link. As a further result of the energization of release relay 122, it opens a point in the circuit of release magnet 126 at armature 134 and closes a point in the circuit of vertical magnet 128, and at armature 132 closes a point in the circuit of the common chain relay 106 for a purpose which will be later pointed out. The first selector is now in readiness to be operated in accordance with the first digit of the desired number. The description of this operation, however, will be deferred until the description of the operation of the common controlling apparatus has been completed.

As a further result of the energization of relay 227, Fig. 3, it disconnects the auxiliary stepping control relay 223 at armature 263 so as to prevent interference from this source at this time, and at armatures 261 and 262 it grounds conductors 272 and 273 respectively, extending to wipers 307 and 310 of the vertical sender VS and the rotary sender RS, Fig. 4. It may be seen that the ground potential on wipers 307 and 310 is extended through the self interrupting contacts 304 and 305 to the magnets 301 and 302. Accordingly, these magnets operate in buzzer like manner with the result that switches VS and RS are returned to their normal position in the usual manner. It will be noted that the ground potential for driving magnets 301 and 302 is

derived through the low wound series guard-control relay 228. Accordingly relay 228 energizes when the restoring circuits are closed and it remains energized until they are both opened on account of the fact that it is slow acting and is able therefore to maintain its armature attracted notwithstanding the interruption in its circuit. It may be pointed out that relay 228 at armature 264 closes a circuit through the lower winding of the relay 227 so as to maintain this relay energized and the restoring circuits of the switches VS and RS intact at armatures 262 until the restoring operation is completed. At armature 265, relay 228 closes a circuit through the resistance 266 and through the switch-room supervisory relay 231 so that an attendant may be informed in case the restoring circuits are not opened within a reasonable length of time.

After the interval for which it is adjusted the slow acting start relay 226 falls back in response to being disconnected at the resting contact and armature 259. At armature 255 relay 226 disconnects the combined cut-through and test conductor (now grounded at the first selector FS) from the cut-through circuit and connects it back to the test circuit again; it opens the circuit of the secondary switching relay 222 at armature 258, and again closes a point in the circuit of busy relay 229, whereupon the relay 222 falls back, but without any particular result at this time; and at armature 257 it opens the circuit of the auxiliary start relay 225. When this occurs relay 225 falls back and removes the local ground from the start conductor 12 at armature 251; reconnects conductor 221 to the terminal 269 at armature 253; and at armature 254 removes ground from wiper 312 of the sequence switch SE and consequently from conductor 278 extending to the upper winding of the guard relay 227 and through armature 209 and its resting contact and conductor 86 to stepping magnet 77 of the finder allotter FA. The upper winding of relay 227, however, remains grounded at this time from the cut-through and test conductor 84 (which picks up ground through wiper 75, spring 50 and its upper contact, armature 47 and its working contact, and the working contact and armature 44, from release trunk conductor 72) through the resting contact and armature 207, armature 255 and its resting contact and the resting contact and armature 267. Stepping magnet 77 of the finder allotter FA, however, now falls back because the shunt is removed from around its contact 78 at armature 252 of relay 225. When stepping magnet 77 of the finder allotter FA falls back it advances the wipers 71-76 one step. In case the finder associated with the second set of bank contacts of the finder allotter FA is busy wiper 75 engages a grounded bank contact with the result that the circuit over con-

ductor 84, for the upper winding of the guard relay is maintained closed from the ground potential encountered by wiper 75. This ground potential is extended through the previously traced circuit to stepping magnet 77 through contact 78. Accordingly the self interrupted magnet 77 advances the wipers 71—76 of the allotter FA to an idle finder. At armature 260, relay 227 maintains conductors 273 and 274 disconnected so as to avoid interference with the busy finders, and at armature 259 it maintains start relay 226 disconnected so as to prevent a premature operation of this relay.

15 When an idle finder is reached, the finder allotter FA ceases to advance and the guard relay 227 falls back and again connects up start relay 226 at armature 259. Also, responsive to the finding of the idle finder, stepping magnet 303 Fig. 4, which in its third position is maintained energized in parallel with the upper winding of guard relay 227 (as hereinbefore pointed out) falls back and advances the wipers 312—314 from the third set 20 of contacts to the fourth set of contacts. The fourth set of contacts are multiplied with the first set of contacts, the fifth set is multiplied with the second set, etc. Accordingly, the sequence switch SE as well as the remaining 25 part of the common equipment is ready to be used in handling another call.

The operation of the first selector FS will now be taken up. When the subscriber at substation A turns his calling device in accordance with the first digit in the desired 30 number, line relay 121 falls back a number of times corresponding to the number of impulses produced at the calling substation. Each time it falls back it closes at armature 131 a circuit through armature 134 and its front contact, series relay 123, and vertical magnet 128 to battery. By the operation of vertical magnet 128, the wipers 143—145 are raised step by step until they come to rest 35 opposite the desired level of bank contacts. Relay 123 is energized in series with vertical magnet 128 and, being slow acting, maintains its armature attracted throughout the series of impulses. At armature 135, relay 123 prepares a circuit for stepping relay 124, which 40 is completed at off normal contacts 130 upon the first upward step of the switch, and which includes, in addition, the interrupter contacts 152 of the rotary magnet 127. Relay 124 energizes when this circuit is closed and it 45 closes a locking circuit for itself at armature 136, and at armature 137 prepares a circuit for rotary magnet 127.

At the end of the vertical movement, the 50 slow acting relay 123 falls back and at armature 135 completes through armature 137 and its working contact the circuit of rotary magnet 127. Rotary magnet 127 now pulls up and advances the wipers 143—145 into engagement with the first set of bank contacts 55

in the selected level. Near the end of its stroke, magnet 127 opens the circuit of stepping relay 124 at contacts 152. Relay 124 thereupon falls back and opens a further point in its own circuit at armature 136, at 70 the same time opening the circuit of rotary magnet 127 at armature 137. Rotary magnet 127 now falls back also and closes its contacts 152 again.

From this point, the operation depends 75 upon whether or not the trunk terminating in the first set of bank contacts is busy or idle. If it is idle, relay 125 now pulls up, seizing the trunk.

Assuming on the other hand that this trunk 80 is busy, relay 125 is short circuited by the ground potential encountered on the busy test contact by test wiper 144 and it does not energize. Relay 124 energizes from this same ground potential and again closes at armature 137 the circuit of rotary magnet 127. When this occurs rotary magnet 127 pulls up again and advances the wiper another step.

This alternate operation of relay 124 and magnet 127 continues as described until an 85 idle trunk is reached, which trunk, it will be assumed, is the one comprising conductors 149—151 and terminating in bank contacts 146—148. When this idle trunk is reached, switching relay 125, being no longer short 90 circuited, energizes in series with relay 124 from the grounded release trunk conductor 109. Relay 124 is not operatively energized at this time on account of the relatively high resistance of relay 125. Upon energizing, relay 125 removes ground from armature 131 of line relay 121 at armature 141, thereby 95 opening the circuit of the slow acting relay 122; it closes a multiple point in the chain circuit at armature 139; it opens the test circuit and prepares the holding circuit at armature 140; and at armatures 138 and 142 it disconnects conductors 108 and 110 from line relay 121 and extends them by way of wipers 143 and 145, bank contacts 146 and 148, and 100 conductors 149 and 151 to the line relay of the switch to which the seized trunk extends. Accordingly, the line and release relays (not shown) of the seized trunk pull up, and the latter grounds the release trunk conductor 110 115 150, thereby completing the usual holding circuit before the slow acting release relay 122 of the first selector FS has had time to fall back.

The remaining part of the establishing of 120 the connection takes place in the usual manner.

It will be noted that the chain circuit is kept closed at the first selector FS subsequent to the falling back of relay 122 at armature 125 139 of relay 125.

At the end of the conversation the subscriber at substation A replaces his receiver, whereupon the ground is removed in the usual manner from release trunk conductor 150 of 130

the trunk seized by the first selector FS, whereupon relay 125 of the first selector FS and relay 36 of the finder F both fall back.

In the selector FS, the deenergization of relay 125 results in the closure of the circuit at release magnet 126 through armatures 141, 131, and 134, and through the off normal contacts 129. Release magnet 126 thereupon energizes with the result that the wipers 143-145 are restored to normal position in the usual manner. The circuits of magnet 125 is opened at off normal contacts 129.

In the finder F, relay 36, upon falling back, removes ground from wiper 32, whereupon cutoff relay 2 falls back and again connects up ground to one line conductor and line relay 3 to the other. Relay 36 also completes the circuit of release magnet 39 at armature 45. The circuit includes armature 48 and its resting contact, armature 45 and its resting contact, and off normal spring 51 at its upper contact. Release magnet 39 now energizes with the result that wipers 31-33 are restored to normal position in the usual manner, whereupon the circuit of release magnet 39 is opened at off normal spring 51.

The entire connection is now released and the apparatus involved therein is ready for use in establishing other connections.

Considering now a call from the subscriber at substation A', whose line terminates in the bank contact set No. 15 in the bank of the finder F, Fig. 1, when the subscriber at substation A' removes his receiver, a circuit is closed for line relay 5. Relay 5 thereupon energizes and at armature 11 places ground upon the common start conductor 12; at armature 19 it closes the No. 15 rotary control circuit over conductors 14 and 15; and at armature 10 it places ground on the first level control conductor 13, thereby closing a circuit through terminal 269 common to the lines of the first level, normally closed contacts controlled by armature 221, and the resting contact and armature 253 for the first level control relay 221. Relay 221 is able to energize, it may be pointed out, before the start relay 226 and the auxiliary start relay 225 have both had time to pull up after the start wire is grounded. Upon energizing, relay 221 closes a locking circuit for itself and opens its initial circuit at armature 242; opens a point in the vertical magnet operating circuit at armature 241 so as to prevent the usual magnet circuit from being closed at this time as the wipers are already opposite the first level of bank contacts; and at armature 243 it opens the circuit for advancing the vertical sender VS and prepares over conductor 281 a circuit for automatically advancing the sequence switch SE, Fig. 4, from its first position to its second position.

Accordingly, when the auxiliary start relay 225 pulls up following the closure of its circuit at armature 257 of start relay 226, it

closes the usual circuits at its armatures 250-252, and at armature 254 places ground on conductor 270, thereby extending ground through armatures 248 and 249 and over conductors 279 and 280 to the sender-impulse and the finder-impulse distributing wipers 312 and 313. The ground potential placed on wiper 313 is extended through conductor 277, armature 243 and its working contact, conductor 281, and the self-interrupting contacts 306 to the stepping magnet 303 of the sequence switch SE. Accordingly, magnet 303 operates and opens its own circuit, whereupon the wipers 313-314 are advanced one step from the vertical sending position to the rotary sending position.

The ground potential on wipers 312 and 313 is now extended in the usual manner to the rotary magnet of the finder F and to magnet 302 of the rotary sender RS in the manner hereinbefore described, and stepping relay 224 is controlled over the common stepping conductor 79 to interrupt the circuits at armatures 248 and 249 in the hereinbefore described manner, thereby advancing the rotary sender RS and the finder F simultaneously.

At the end of the fourth step of the finder F and of the rotary sender RS, the wiper 311 of the rotary sender RS is standing on the fifth associated bank contact. Accordingly, when the impulse circuit is again closed, upon the falling back of the stepping relay 224, a circuit in multiple with magnet 302 is closed through the vertical marking wiper 309 of the vertical sender VS in its first position, terminal 294, conductor 14, working contact and armature 9 of line relay 5, conductor 15, terminal 293, fifth contact in the bank of the rotary control wiper 311 and said wiper, second contact in the bank of wiper 314 and said wiper, and stepping magnet 303 of the sequence switch SE to battery. Accordingly, magnet 303 is energized in multiple with the rotary magnet 35 of the finder F. As soon as the impulse is terminated, upon the pulling up of stepping relay 224, Fig. 3, the sequence switch SE advances from its second position to its third position with the hereinbefore described results. From this point on the operation is the same as described hereinbefore and need not be repeated.

Certain points in connection with the circuits shown, which are not conveniently described in the course of a call will now be pointed out a little more in detail. Considering first the arrangement whereby the secondary switch SS, Fig. 1, is made preselecting, it will be noted that, with the finder allover FA, Fig. 1, standing on the finder and with the remaining part of the equipment in the normal position shown, the test wiper 102 of the secondary switch SS is connected to the stepping magnet 104 through the IDF jumper 54, release trunk conductor 72 of the

finder F, first contact in the bank of wiper 72 of the finder allotter FA and said wiper, conductor 82, resting contact and armature 205, armature 245 and its resting contact, 5 resting contact and armature 260 of the guard relay 227, armature 28 and its resting contact, conductor 85, wiper 76 and the first associated bank contact, IDF jumper 55, and the self-interrupting contacts 105. Accordingly, 10 the magnet 104 is operated in the usual manner to advance the switch to an idle trunk if it is not already on one. Furthermore, it will be noted that there is normally no circuit for pulling up the secondary 15 switching relay 222, Fig. 3. Accordingly, when the secondary switch SS reaches an idle trunk when there is no calling line to be found by the allotted finder, the idle trunk is not made busy. This trunk is left idle because, 20 considering a particular secondary group, the various secondary switches in this group are associated with finder switches in different hundred-line groups. Accordingly, if there are only a few idle trunks in the 25 group, it is best not to actually make a trunk busy to the exclusion of use by other secondary switches until a call comes in. The switching relay circuit remains open at armature 258 and its working contact of start relay 30 226 until the said start relay pulls up. Start relay 226 also, it will be noted, shunts the resting contact and armature 260 at armature 256 so as to maintain the connection between the test wiper 102 and the stepping magnet 104, 35 Fig. 2, independent of the resting contact and armature 260 of the guard relay 227.

A certain point now in connection with the rendering of the finders, such as F, busy to the finder allotter FA will now be considered. 40 It will be noted that the release-guard conductor 83 is extended through the wiper 74 and its first associated contact to the release guard relay 37 of the finder F. Accordingly, when the release guard conductor 83 is 45 grounded at armature 250 of the auxiliary start relay 225, as hereinbefore pointed out, the release guard relay 37 pulls up and remains up as long as the auxiliary start relay remains energized. It will be noted that the 50 cut-through conductor 84 is extended through the cut-through wiper 75 to off normal spring 50, and that as soon as the release-guard relay 37 pulls up a ground potential is placed at armature 48 on off normal spring 50 through the lower contacts thereof, thereby extending a ground potential down to the cut-through wiper 75 which is used also as a test wiper. This does not have any particular utility at this time, however, on account 55 of the fact that the cut-through wiper is disconnected from the test branch at armature 255 of start relay 226 at this time. However, when the release-guard relay 37 is pulled up 60 through the IDF jumper 53 and through the

off normal contacts 49 of the finder F, responsive to the energization of the chain relay 107, Fig. 2, when all the first selectors such as FS are busy, the ground potential placed through armature 48 and its working contact, and the resting contact and spring 50 on the first contact in the bank of wiper 75 is effective in advancing the finder allotter FA to the next set of bank contacts, provided the common controlling mechanism is in the normal position shown, or is in the position of testing for an idle finder immediately after the completion of the call. 65

It may be pointed out further that the finder F is maintained busy to the finder allotter FA subsequent to the falling back of the release-guard relay 37 as soon as the common controlling apparatus is through setting the finder F, not from the release trunk conductor 72, but from the local ground through the resting contact and armature 47, and through the upper contact and off normal spring 50. Accordingly, this ground potential is available for guarding the finder F until the off normal springs shift back to their normal position shown in the drawings when the finder is finally released. 80

Regarding the auxiliary stepping relay 223, Fig. 3, this relay is slow to pull up and it does not therefore have time to pull up in the ordinary operation. In case, however, that the finder being operated is not able to ground conductor 79 to control the regular stepping relay 224, the circuit closed through the working contact and armature 254, resting contact and armature 263, and armature 247 and its resting contact for the auxiliary stepping relay 223, is effective in energizing this relay in a period of time somewhat longer than ordinarily required for energizing the operating magnet of the finder. Upon energizing, relay 223 closes at armature 246 a local circuit for stepping relay 224, whereupon relay 224 energizes to open the impulsing circuit at armatures 248 and 249 and to open the circuit of the auxiliary stepping relay 223 at armature 247. Relay 223 now falls back fairly quickly, notwithstanding the copper slug on the armature end of its core, owing to its stiff adjustment, and at armature 246 opens the circuit of stepping relay 224 which thereupon falls back to send the next impulse. 100

Referring now to the sequence switch SE, Fig. 4, it will be noted that the circuits closed during the second three positions of the sequence switch are the same as the circuits closed during the first three positions of the switch, respectively. The same, it will be noted, is true of positions seven, eight and nine. In positions ten and eleven, however, wipers 313 and 314 both encounter dead contacts and wiper 312 is connected with contacts wired to the stepping magnet 308 through the self-interrupting contacts 306. 115

Accordingly, when the sequence switch SE advances to position ten at the end of the call which occupies positions seven, eight and nine of the sequence switch SE, a circuit is prepared for magnet 303 which is closed over conductor 279 upon the next energization of the auxiliary start relay 225. When this circuit is closed the magnet 303 advances the wipers 312—314 through positions ten and eleven and into position one again, whereupon the allotted finder is started into operation in the usual manner.

Regarding the busy relay 229, Fig. 3, this relay is normally included in the circuit from ground through armature 258 and its resting contact, relay 229 and resistance 230 to battery. However, the normally grounded conductor 88, which is common to all the associated finders, is connected at the junction 20 of relay 229 and resistance 239. Conductor 88, it will be noted, is grounded in the finder F through armature 48 and its resting contact, armature 45 and its resting contact, and off normal spring 51 and its lower contact. 25 When the finder F is in use, however, this ground potential is removed from conductor 88, first at armature 48 and subsequently at off normal spring 51. When all finders are in use, the ground is completely removed from 30 conductor 88, whereupon busy relay 229 pulls up and prevents the operation of the finder allotter FA at armature 267 which is separated from its resting contact. Also, busy relay 229 closes at armature 268 a circuit through the lower winding of relay 227, which 35 thereupon pulls up and disconnects start relay 226, etc. The reason for taking the circuit of relay 229 through armature 228 and its resting contact is to prevent the premature operation of busy relay 229 when the call comes in that is to take the last available 40 finder.

What is claimed is:

1. In a telephone system, a two-motion finder switch, a calling line terminating in the bank thereof, primary and secondary magnets for driving said finder in its respective movements, means for sending a single train of impulses to said finder, and means independent of control by said impulses for diverting the first part of said series to said primary magnet and for diverting the remaining part to said secondary magnet, whereby said finder is set upon the bank contacts of the calling line.
2. In an electrical controlling system, a plurality of operating magnets, means for generating a single series of similar impulses each similarly spaced from the others, and 50 synchronously operated counting controlled mechanism for distributing said impulses amongst said magnets in any one of several predetermined combinations.
3. In an electrical controlling system, two

impulse paths, means for transmitting a series 65 of electrical impulses over the first of said paths, and means operated simultaneously with the transmission of a predetermined one of said impulses over the first path for diverting remaining impulses of the series over 70 the second path.

4. In an electrical controlling system, an impulse generator, a path for the impulses generated thereby, and means operated simultaneously with the generation of only 75 one of said impulses for barring further impulses from traversing said path.

5. In an electrical controlling system, an impulse generator, a path for the impulses generated thereby, and means comprising a 80 step-by-step switch operated by only one of the impulses transmitted over said path for barring further impulses from passing over said path.

6. In a directive finder switch system in 85 which the finder switches are of the two-motion type, a finder controlling arrangement comprising an impulse generator, a primary motion counting switch having progressively 90 movable wipers, a secondary motion counting switch having progressively movable wipers, and a counting-switch-control sequence switch having progressively movable wipers.

7. In a vertical and rotary finder switch system for use in telephone systems in which common sending mechanism is used to set the finders on calling lines, a register associated with the sending mechanism for registering the extent of the primary operation of an operated finder to place the further operation of the sending apparatus under the exclusive control of calling lines in the group selected by the primary operation of the finder.

8. In an electrical controlling system, an impulse generator for generating two series of impulses, two counting switches for counting said series, respectively, connections controlled exclusively by the first counting switch for terminating the first series of impulses, and connections controlled jointly by the two switches for terminating the second series of impulses.

9. In a step-by-step finder switch system for use in telephone systems, a relay having 115 a contact for transmitting impulses to the operating magnets of the finders, an allotter for connecting said contact to an idle finder, and means controlled by the operating magnets of the allotted finder for controlling said 120 relay to operate said contact.

10. In a step-by-step finder switch system for use in telephone systems, a relay having a contact for transmitting impulses to the operating magnets of the finders, an allotter for connecting said contact to an idle finder, means controlled by the operating magnets 125 of the allotted finder for controlling said re-

lay to operate said contact, and timing means for exercising control over said relay in case the magnets of the finder are unable to do so.

11. In a telephone system employing finder switches, numerical switches, a secondary line switch connected to each finder switch, means for allotting an idle finder switch for use before a call is received, and means for thereupon causing the secondary switch connected with the allotted finder to select an idle numerical switch.

12. In a telephone system employing finder switches, numerical switches, a secondary line switch connected to each finder switch, means for allotting an idle finder switch for use before a call is received, means for thereupon causing the secondary switch connected with the allotted finder to select an idle numerical switch, and means responsive to a call for rendering the selected numerical switch busy to other secondary switches.

13. In an electrical controlling system, an impulse generator for generating a series of evenly spaced impulses, a counting switch having wipers and a magnet, said magnet being energized by said impulses to advance said wipers to count said impulses, contacts engaged by said wipers, means for marking a certain one of said contacts to define a group of said impulses, a plurality of paths for said impulses, means controlled through said marked contact and counting switch wiper which engages it, for ending said group by diverting the remaining impulses of the series to another of said paths.

14. The method of preventing number scrambling, of simultaneous calls received by a control mechanism, by registering the level designations of the calling lines in a level selecting control, by preparing circuits for registering the contact designations of the lines in a contact selecting control, and by closing said circuit after said level selecting control has been positioned, to register the contact designations of only those calling lines which are in the selected level.

15. In a telephone system, a group of finder switches having banks, a plurality of groups of lines terminating in said banks each of said groups comprising a level in said banks, a common control mechanism comprising a sender for delivering impulses to said finders, a plurality of counting switches and a sequence switch, means individually associated with each of said lines and responsive to a call thereon to start said control equipment functioning, to mark the level containing the line in one of said counting switches and to prepare a loop for marking the line in another of said counting switches, means responsive to the starting of said control equipment to position said one counting switch on said marked contact and to position one of said finders on the level corresponding thereto, and means for then closing a circuit

through said sequence switch, said first counting switch and said loop to said other counting switch to register said line designation therein preparatory to positioning said finder thereon.

16. In a telephone system, a plurality of lines arranged in level groups, finder switches having access thereto, control devices for said finders comprising primary and secondary motion controls, marking devices individual to each line, means responsive to simultaneous calls on lines of different levels for operating the respective marking devices to register the level designations of said lines in said primary motion control and to prepare a point in the line designation circuits of said lines, means in said control device operated in response to the operation of said marking devices to select a certain designated level, and means then operated to complete said prepared line registration circuits of the lines in said selected level, to register those lines in the secondary motion control preparatory to governing that control.

17. In an electrical impulsive system, a plurality of magnets, a relay containing a contact for closing a circuit to one of said magnets and to a second relay, contacts operated by said magnets to close a circuit to said first relay to open said magnet circuit, and means controlled by said second relay after a definite interval, to operate said first relay if said magnet contacts fail.

18. In a telephone system, a plurality of finder switches each having a plurality of magnets, a common control equipment, an allotter for associating said control equipment with said one of said finders, a stepping relay in said control equipment having contacts through which a circuit is closed to said finder magnets in order, a retractive pulse conductor extending from said stepping relay to said finders independently of said allotter, and means operated by said magnets to operate said stepping relay over said conductor to open said magnet circuit.

19. The method of controlling the speed at which impulses are generated by an impulsive device, which consists of closing a circuit to the magnet which is to be impelled, and of closing a pulse terminating circuit by contacts closed by that magnet when it is in its fully operated position.

20. In a telephone system, a plurality of lines terminating in a switch bank having levels, a finder switch having wipers which normally stand opposite one of said levels, a shaft supporting said wipers, a control means for operating said finder step-by-step to position said wipers upon one of said line terminals either in the level opposite which said wipers are standing or in any other level, contacts on said finder switch, and shaft controlled means for operating said contacts

during the first step operation irrespective of the direction the shaft is moved by that step.

21. In a telephone system, a group of lines, 5 a group of finder switches having access thereto, secondary switches connected to said finder switches, a group of numerical switches accessible to said secondary switches, a control equipment common to said finder 10 switches, an allotter for associating said control equipment with one of said finder switches, a start relay in said control equipment energized in response to a call on one of said lines to start said equipment functioning to position the allotted finder on that 15 line and to establish a connection therewith, means associated with said line and responsive to the establishment of said connection to deenergize said start relay, means responsive to that deenergization of said start relay for operating said allotter to connect another 20 finder with said control and to operate the secondary switch associated with said another finder to select a numerical switch and 25 means responsive to a subsequent energization of said start relay for rendering said numerical switch busy to other secondary switches.

22. The method of controlling the stepping in sequence of the two magnets of a switch, which consists; of generating continuous series of uniform impulses, the first part of which is counted out to the first of said magnets; of energizing a pulse diverting means 30 by the last impulse so counted; and of diverting said impulses so that the next and succeeding impulses are counted out to the second of said magnets.

23. In a telephone system; a plurality of lines terminating in a switch bank having 40 levels, a finder switch having wipers which normally stand opposite one of said levels, a primary magnet for moving said wipers to select one of said levels, a secondary magnet for moving said wipers to select a line in a 45 selected level, control means responsive to the initiation of a call on one of said lines for operating said magnets in turn, to position said wipers on the contacts of said line, and means responsive to the initiation of a call 50 on a line in the level opposite which said wipers normally stand for altering said control means to operate said second magnet only, to position said wipers on the contacts 55 of said calling line.

24. In a telephone system, a plurality of lines terminating in a switch bank having 60 levels, a finder switch having wipers which normally stand opposite one of said levels, a primary magnet for moving said wipers to select one of said levels, a secondary magnet for moving said wipers to select a line in a selected level, control means responsive to the initiation of a call on one of said line for operating said magnets in turn, to position 65 said wipers on the contacts of said line, and a relay energized in response to the initiation of a call in the level opposite which said wipers normally rest for removing said primary magnets from said control means and operating said secondary magnets to position 70 said wipers on the contacts of said calling line.

In witness whereof, I hereunto subscribe my name this 9th day of May, A. D. 1925.

RUDOLPH F. STEHLIK.
